UNITED STATES PATENT OFFICE.

EUGENE H. HELLER, OF CHICAGO, ILLINOIS, ASSIGNOR TO THE HILL PUMP VALVE COMPANY, OF CHICAGO, ILLINOIS, A CORPORATION OF ILLINOIS.

DESIGN FOR AN AUTOMOBILE-HEATER.

53,124.

Specification for Design.

Patented Mar. 25, 1919.

Application filed January 10, 1917. Serial No. 141,684. Term of patent 7 years.

To all whom it may concern:

Be it known that I, EUGENE H. HELLER, a citizen of the United States, residing at Chicago, in the county of Cook and State of Illinois, have invented a new and original and ornamental Design for Automobile-Heaters, of which the following is a specification, reference being had to the accompanying drawing, forming a part thereof.

The figure is a perspective view of the heater.

I claim:

The ornamental design for an automobile heater as shown.

EUGENE H. HELLER.
